CLAIM

The ornamental design for a bottle, as shown and described.

DESCRIPTION

FIG. 1 is a perspective view of a bottle showing our new design;

FIG. 2 is a front view thereof, the rear, right side and left side views being substantially identical;

FIG. 3 is a top view thereof; and,

FIG. 4 is a bottom view thereof.

The broken lines in FIGS. 1–4 are included for the purpose of illustrating environment and form no part of the claimed design.

1 Claim, 3 Drawing Sheets
